ABSTRACT OF THE DISCLOSURE

An electronic oven is disclosed including a cooking cavity and a source of microwave energy coupled thereto by a coaxial-type transmission line the inner conductor of which comprises two spaced-apart sections defining therebetween a gap of a predetermined length, and a two-position phase-matching apparatus including two electrically conductive members of different lengths not less than the predetermined length for phase matching the source to the cooking cavity when either thawed or frozen foods are disposed therein by bridging the gap with one or the other of the conductive members respectively when the apparatus is in its first or second positions.

The present invention relates to electronic or microwave ovens, and especially to transmission lines for coupling a source of high frequency electromagnetic wave energy to a cooking cavity. In particular, this invention relates to phase-matching devices for such transmission lines for phase matching the source to the cooking cavity.

It is an important object of this invention to provide an electronic oven including a cooking cavity, a generator of high frequency electromagnetic wave energy and a transmission line coupling the generator to the cooking cavity, and which is capable of effectively heating both thawed foods and frozen foods.

It is another object of this invention to provide an electronic oven including a cooking cavity for heating both thawed foods and frozen foods and a generator for generating high frequency electromagnetic wave energy and a transmission line coupling the generator to the cooking cavity and phase-matching apparatus having first and second conditions respectively phase matching the source to the cooking cavity when either thawed foods or frozen foods are disposed therein.

In connection with the foregoing object, it is another object of this invention to provide an electronic oven of the character described wherein the transmission line has a hollow outer conductor surrounding an inner conductor, said inner conductor having a gap therein between the generator and the cooking cavity of a predetermined length, and wherein the phase-matching apparatus has first and second positions and includes two electrically conductive members of different lengths not less than the gap length, one of the members bridging the gap when the phase-matching apparatus is in its first position and the other of the members bridging the gap when the phase-matching apparatus is in its second position.

In connection with the foregoing object, it is yet another object of this invention to provide an electronic oven of the character described wherein the phase-matching apparatus includes a support member extending into the gap and being movable between a first position and a second position and two electrically conductive contact members of different lengths not less than the gap length mounted on the support member and drive means for moving the support member between the first and second positions thereof.

In connection with the foregoing object, still another object of this invention is to provide an electronic oven

of the character described wherein the support member is an elongated rod extending through the gap normal to the longitudinal axis of the transmission line adjacent to the gap, and wherein one of the conductive members has a first length slightly greater than the gap length and is mounted on the rod intermediate the ends thereof and the other contact member has a second length greater than the first length and exceeding the gap length by a length no greater than one half of the wave length of the operating frequency of the generator and is mounted on the rod adjacent to one end thereof and wherein the drive means is connected to the rod adjacent to the other end thereof.

In connection with the foregoing object, a still further object of this invention is to provide an electronic oven of the character described wherein one of the contact members has a first length not less than the gap length and is mounted on the rod adjacent to one end thereof and wherein the other contact member has a second length greater than the first length and exceeding the gap length by a length no greater than one half of the wavelength of the operating frequency of the generator and is mounted on the rod intermediate the ends thereof.

Another object of this invention is to provide, for use in an electronic oven, a phase-matching apparatus including a transmission line having a hollow outer conductor surrounding an inner conductor for transmitting high frequency electromagnetic wave energy, said inner conductor having a gap therein of a predetermined length, and two-position bridging means including two electrically conductive contact members of different lengths not less than the predetermined length for bridging the gap with one or the other of the contact members respectively when the bridging means is in the first or second position thereof, whereby changing the position of the bridging means serves to change the effective electrical length of the transmission line to accomplish a shifting of the phase of the high frequency electromagnetic wave energy transmitted therealong.

40 In connection with the foregoing object, it is another object of this invention to provide a phase-matching apparatus of the character described wherein the bridging means includes an elongated rod extending through the gap normal to the longitudinal axis of the transmission line adjacent to the gap and being movable between a first and second position and wherein a first one of the contact members has a first length slightly greater than the gap length and is mounted on the rod intermediate the ends thereof and wherein a second one of the contact members has a second length exceeding the gap length by a length no greater than one-half of the wavelength of the predetermined frequency and is mounted on the rod adjacent to one end thereof and wherein the apparatus further includes drive means connected to the rod adjacent to the other end thereof for moving the rod between the first and second positions thereof.

In connection with the foregoing object, it is another object of this invention to provide phase-matching apparatus of the character described wherein the first contact member has a first length not less than the gap length and is mounted on the rod adjacent to one end thereof and wherein the second contact member is mounted on the rod intermediate the ends thereof.

The invention, both as to its organization and method of operation together with further objects and advantages thereof, will best be understood by reference to the following specification taken in connection with the accompanying drawings, in which:

FIG. 1 is a perspective view of an electronic oven according to the invention, portions thereof being shown in broken lines;

FIG. 2 is a schematic and diagrammatic illustration of an electronic oven according to the invention showing the controls for the phase-matching apparatus;

FIG. 3 is a sectional view of the phase-matching apparatus according to a first embodiment of this invention shown in the position for use with frozen foods;

FIG. 4 shows the apparatus of FIG. 3 in the position for use with thawed foods;

FIG. 5 is a sectional view of a second embodiment of the phase-matching apparatus according to the invention shown in the position for use with thawed foods;

FIG. 6 is a view of the apparatus of FIG. 5 shown in the position for use with frozen foods; and

FIG. 7 is a graph plotting several operating characteristics of the microwave generator for the oven according to this invention with the loading characteristics of several types of foods superimposed thereon.

Referring now to the drawing, in particular to FIG. 1 thereof, there is shown an electric range generally designated by the numeral 70 including therein an electronic oven 72 according to the invention which comprises a cooking cavity 75, a generator 80 for generating high frequency or microwave electromagnetic wave energy, a transmission line 85 interconnecting the cooking cavity 75 and the microwave generator 80 and a phase-matching device 100. The range 70 is defined by an upstanding substantially box-like wall structure generally designated by the numeral 90, including a top wall, a bottom wall, a front wall, a back wall, and a pair of opposed side walls. The front wall is provided with a front door 92 movable between a substantially vertical closed position and a substantially horizontal open position and opening into the cooking cavity 75. For this purpose there is provided on the door 92 a handle 94. Supported by the top wall of the range 70 is plurality or surface heating units generally designated by the numeral 95, which heating units 95 are preferably of the sheathed resistance conductor type.

Connected to one end of the transmission line 85 adjacent to the cooking cavity 75 and extending thereto is an antenna structure 89 for radiating microwave energy into the cooking cavity 75.

A suitable source of microwave energy for use in operating the microwave oven 72 is shown in FIG. 1 of the drawing and is generally designated by the numeral 80. One preferred source of microwave energy is a crossed field electron discharge device in the form of a multiple cavity magnetron device of the type illustrated and described in U.S. Pat. No. 3,377,562 which issued on Apr. 9, 1968 to James E. Staats. The magnetron device described in that patent is particularly well suited for incorporation in electronic cooking apparatus such as the microwave heating oven 72 of the present invention. More particularly, this magnetron device is designed to oscillate at an ultra high frequency of about 915 mhz., employing anode-cathode voltages in the general range 250 to 1,000 volts D.C. with corresponding R.F. power outputs in the general range 80 to 2,400 watts. Specifically, at a plate voltage of about 290 volts D.C., this magnetron device has a continuous R.F. power output of about 100 watts at the ultra high frequency of 915 mhz.; at a plate voltage of about 570 volts D.C., this magnetron device has a continuous R.F. power output of about 700 watts at the ultra high frequency of 915 mhz.; and at a plate voltage of about 1,000 volts D.C., this device has a peak R.F. power output of about 2,400 watts at the ultra high frequency of 915 mhz.

By using suitable control and power supply systems, which are also described in detail in the aforementioned U.S. Pat. No. 3,377,562, the above-described magnetron device can be readily operated from the usual household three-wire Edison network of 236 volts single-phase, 60-cycles A.C.

The microwave energy produced by the generator 80 is coupled to the cooking cavity 75 by the transmission line 85. The transmission line 85 is preferably of the co-

axial type having a hollow outer conductor surrounding an inner conductor. The inner conductor may be either hollow or solid, but is preferably solid, and both the outer conductor and inner conductor may have either a rectangular or circular cross section, as long as each has the same shape cross section.

Disposed in the transmission line 85 between the generator 80 and the cooking cavity 75 is a phase-matching device 100, which will now be described in detail. Referring to FIGS. 3 and 4 of the drawing, there is shown a two-position phase-matching apparatus 100 according to a first embodiment of this invention. The apparatus 100 is shown in connection with a transmission line 85 including a hollow outer conductor 86 preferably being substantially rectangular in cross section and surrounding a solid inner conductor 88 which has a thin strap-like shape of rectangular cross section. The outer conductor 86 has a first opening 101 therein. The opening 101 may be either circular or rectangular in outline, but is preferably rectangular. Covering the opening 101 is an outer conductor section designated by the numeral 102 which may be either box-like or cylindrical in shape, but is preferably box-like. The outer conductor section 102 includes a top portion 103 integral with and disposed substantially normal to side walls 104 at one end thereof. The side walls 104 extend outwardly from the outer conductor 86 substantially normal to the longitudinal axis thereof and are supported thereon by supporting flanges 105 which are integral with and extend outwardly from and normal to the side walls 104 at the other ends thereof. The outer conductor section 102 thereby defines a housing covering the opening 101. The inner conductor 88 comprises two sections 106 and 107, terminating respectively at up turned end flanges 108 and 109, defining therebetween a gap of a predetermined length generally designated by the numeral 110. The inner conductor section 106 is separated from and supported upon the outer conductor 86 by a cylindrical insulating spacer 111 fastened therebetween adjacent to the inner conductor section end 108 by suitable fastening means 112. The inner conductor section 107 is similarly separated from and mounted upon the outer conductor 86 by an insulating spacer 113 fastened therebetween adjacent to the inner conductor section end 109 by fastening means 114.

The outer conductor 86 has a second opening 115 disposed on the opposite side of the outer conductor 86 from the opening 101 and coaxial with the opening 101 and the gap 110. The opening 115 is preferably circular in outline and is substantially smaller in area than the opening 101.

A support member 120 comprising an elongated rod of circular cross section is disposed through the openings 101 and 115 and the gap 110 and is coaxial therewith. One end of the rod 120 extends into the outer conductor section 102 and the other end extends outwardly beyond the outer conductor 86. The rod 120 is axially movable between first and second positions. A first contact member generally designated by the numeral 125 is mounted on the rod 120 intermediate the ends thereof. The contact member 125 includes an insulating mounting portion 126 substantially annular in shape and connected to the rod 120. Surrounding the mounting portion 126 and attached thereto is an electrically conductive contact portion 128 which is a thin, flat plate, preferably rectangular in shape. The longitudinal extent of the contact portion 128 is slightly greater than the length of the gap 110. The contact member 125 is disposed between the outer conductor 85 and the inner conductor 88 adjacent to the opening 115. Disposed on the outer side of the contact portion 128 is an annular stop element 129 having an outer diameter greater than the diameter of the opening 115 in the outer conductor 86. The stop member 129 is arranged to bear against the inner surface of the outer conductor 86 adjacent to the opening 115 when the rod 120 is in a first one of its two positions to prevent further outward axial

movement of the rod 120. A second contact member generally designated by the numeral 130 is connected to the rod 120 at the end thereof which extends into the outer conductor section 102. The contact member 130 is substantially U-shaped and is made of an electrically conductive material. The contact member 130 has a flat strap-like shape rectangular in cross section and is bent to form a bight 131, a pair of substantially parallel legs 132 and 133 integral with and disposed substantially normal to the bight 131 and a pair of guide flanges 134 and 135 bent slightly inwardly toward one another at the free ends of the legs 132 and 133. The end of the rod 120 which extends into the outer conductor section 102 has a portion 136 which is reduced in diameter and externally threaded. The contact member 130 is attached to the rod 120 at the threaded portion 136, the bight 131 having a centrally positioned opening therethrough into which is fitted the threaded end 136. A nut 137 secures the contact member 130 to the rod 120. The contact member 130 is so attached to the rod 120 that the legs 132 and 133 extend toward the gap 110 so as to respectively contact the inner conductor section ends 108 and 109 when the rod 120 is in its first position.

Attached to the other end of the rod 120 externally of the outer conductor 86 is a drive means generally designated by the numeral 140. The drive means 140 includes an annular bearing bracket generally designated by the numeral 141 which is substantially cylindrical in shape and is disposed in surrounding relationship to the rod 120 adjacent to the outer end thereof. The bearing bracket 141 includes an annular side wall 142 surrounding and coaxial with the rod 120 and having at the outer end thereof integral therewith and disposed substantially normal thereto an inwardly extending annular flange 143 and having at the inner end thereof integral therewith and disposed substantially normal thereto an outwardly extending annular mounting flange 144. The mounting flange 144 is fastened to the outer surface of the outer conductor 86 so that the bearing bracket 141 overlies the opening 115 in the outer conductor 86. The plate 142 has a centrally positioned circular opening 145 therein substantially the same size as the coaxial with the opening 114. The drive means 140 further includes a substantially annular retaining bracket generally designated by the numeral 146. The retaining bracket 146 includes a side wall 147 surrounding and coaxial with the side wall 143 of the bearing bracket 141 and extending outwardly therefrom beyond the plate 142. At the outer end of the side wall 147 is an annular flange 148 disposed substantially normal to the side wall 147 and integral therewith and defining a circular opening 149 therethrough. The inner end of the side wall 147 abuts the mounting flange 144 of the bearing bracket 141. Disposed within the retaining bracket 146 is an annular solenoid coil 150 which extend from the plate 143 of the bearing bracket 141 axially outwardly to the flange 148 of the retaining bracket 146. Surrounding that portion of the rod 120 which extends through the opening 115 in the outer conductor 86 and outwardly therefrom is an insulating sleeve 152. The rod 120 and the sleeve 152 extend outwardly through the opening 145 in the plate 142 of the bearing bracket 141. Surrounding that portion of the rod 120 which extends outwardly beyond the bearing bracket 141 and disposed within the annular coil 150 is a coil spring 154. A retaining nut 155 having a diameter slightly greater than the outer conductor of the coil spring 154, but less than the inner diameter of the solenoid coil 150 is attached to the rod 120 at the outer end thereof. The retaining nut 155 serves to retain the coil spring 154 within the coil 150 when the rod 120 is in its first position.

In operation, when in the position shown in FIG. 3 the rod 120 is maintained in this position by the biasing force of the coil spring 154 against the retaining nut 155. In this position the stop element 129 bears against

the inner surface of the outer conductor 86 to prevent further outward axial movement of the rod 120 under the biasing action of the spring 154. Also, in this position the guide flanges 134 and 135 at the free ends of the legs 132 and 133 extend into the gap 110 and the legs 132 and 133 respectively contact the inner conductor section end flanges 108 and 109 at points 156 and 157, thus completing an electrically conductive path from the inner conductor section 107 along the contact member 130 to the inner conductor section 106. In this position the contact member 125 does not contact the inner conductor section ends 106 and 107. The length along the contact member 130 from inner conductor section end 108 to inner conductor section end 109 is such as to properly phase match microwave generator 80 to the cooking cavity 75 when frozen foods are disposed therein.

The solenoid coil 150 is energized from an electrical source to be described hereinafter. When so energized, the rod 120, which is the plunger of the solenoid, is moved inwardly under the action of the magnetic field generated by the solenoid to the position shown in FIG. 4. In this position the retaining nut 155 compresses the spring 154 against the retaining bracket 141. The contact portion 128 of contact member 125 comes in contact with each of the outer conductor section ends 108 and 109, thereby electrically bridging the gap 110. Also, in this position the contact member 130 is disposed out of engagement with the inner conductor section ends 108 and 109. The distance along the contact portion 128 from the inner conductor section end 109 to the inner conductor section end 108 is such as to properly phase match the generator 80 to the cooking cavity 75 when thawed foods are disposed therein.

Referring now to FIGS. 5 and 6 of the drawing, there is shown a two-position phase-matching apparatus 200 according to a second embodiment of this invention. The phase-matching apparatus 200 is shown disposed in a transmission line including a hollow outer conductor 96 and a solid inner conductor 98, each of which has a circular cross section. The inner conductor 98 comprises a pair of sections 206 and 207 terminating respectively in a pair of flattened ends 208 and 209 defining therebetween a gap of a predetermined length generally designated by the numeral 210. Surrounding the inner conductor section 206 adjacent to the end 208 thereof is an annular insulating spacer 211 which serves to center the inner conductor section 206 within the outer conductor 96. Similarly, an annular insulating spacer 213 surrounds inner conductor section 207 adjacent to end 209 thereof. The outer conductor 96 has an opening 215 therein which is generally circular in outline. Connected to the outer conductor 96 in surrounding relationship with the opening 215 is an annular outer conductor section 216 which extends outwardly from the outer conductor 96 substantially normal to the longitudinal axis thereof adjacent to the opening 215. Disposed within the outer conductor section 216 adjacent to the outer end thereof is an annular insulating spacer 218 having a centrally positioned circular opening 219 therein.

A support member 220 in the form of an elongated rod is disposed in the outer conductor section 216 coaxially therewith, one end thereof extending inwardly into the gap 210 and the other end thereof extending outwardly through the opening 219 in the insulating spacer 218 and therebeyond. The rod 220 is axially movable between a first position and a second position to be defined hereinafter. Attached to the rod 220 at the inner end thereof is a first contact member generally designated by the numeral 225 which comprises an electrically conductive thin strap-like member bent to form a flat elongated portion 226 and a pair of end flanges 227 integral therewith and disposed substantially normal thereto and each extending in the same direction. The distance along the contact member 225 between the outer surfaces of the end flanges 227 is substantially equal to and not less than

the length of the gap 210. The inner end of the rod 220 has a threaded portion 228 of reduced diameter which is fitted through a suitable centrally positioned opening in the contact member 225. A nut 229 securely fastens the contact member 225 to the rod 220. The contact member 225 is fastened to the rod 220 so that the end flanges 227 extend outwardly toward that portion of the outer conductor 96 which is directly opposite the opening 215. Attached to the rod 220 intermediate the ends thereof is a second contact member generally designated by the numeral 230 and being substantially U-shaped. The contact member 230 is formed from an electrically conductive thin strap-like material of rectangular cross section which is bent to form a bight 231 and a pair of substantially parallel legs 232 and 233 integral therewith and disposed substantially normal thereto. At the free ends of the legs 232 and 233 are a pair of end flanges 234 and 235 respectively integral with the legs 232 and 233 and extending outwardly therefrom substantially normal thereto. The bight 231 has a centrally positioned circular opening therein accommodating the rod 220 therethrough and is connected to the rod 220 thereat. The contact member 230 is so connected to the rod 220 that the legs 232 and 233 extend inwardly toward the gap 210. The distance between the outer ends of the end flanges 234 and 235 is slightly greater than the length of the gap 210.

Coupled to the rod 220 adjacent to the outer end thereof is a drive means generally designated by the numeral 240. The drive means 240 includes a bearing bracket generally designated by the numeral 241 which is substantially annular in shape and surrounds the rod 220 adjacent to the outer end thereof. The bearing bracket 241 includes an annular side wall 242 surrounding and coaxial with the rod 220 and having at the outer end thereof integral therewith and disposed substantially normal thereto an inwardly extending annular flange 243 and having at the inner end thereof integral therewith and disposed substantially normal thereto an outwardly extending annular mounting flange 244. The flange 244 is connected to the outer conductor section 216 at the outer edge thereof. The annular flange 242 defines an opening 245 therethrough coaxial with and of substantially the same diameter as the opening 219 in the insulating spacer 218 and accommodating the outer end of the rod 220 therethrough. An annular retaining bracket 246 surrounds the bearing bracket 241. The retaining bracket 246 includes an annular side wall 247 surrounding and contacting the outer surface of the bearing bracket side wall 242 and extending outwardly beyond the flange 243 thereof. The inner end of the side wall 247 abuts and is connected to the mounting flange 244 of the bearing bracket 241. At the outer end of the side wall 247 is an inwardly extending annular flange 248 defining a circular opening 249 therethrough. An annular solenoid coil 250 is disposed within the retaining bracket 246 and extends axially between the flange 243 of the bearing bracket 241 and the flange 248 of the retaining bracket 246. Disposed within the bearing bracket 241 and surrounding the rod 220 is an annular stop member 253, having an outer diameter greater than the diameter of the openings 219 and 245. Disposed within the annular solenoid coil 250 and surrounding that portion of the rod 220 which extends outwardly beyond the flange 243 of the bearing bracket 241 is a coil spring 254. Attached to the rod 220 at the outer end thereof is a retaining nut 255 having an outer diameter less than the inner diameter of the solenoid coil 250, but not less than the outer diameter of the spring 254.

In operation, when the rod 220 is in the position shown in FIG. 5 the solenoid coil 250 is not energized and the rod 220 is maintained in the position shown by the biasing action of spring 254 against the retaining nut 255. In this position, the flanges 227 of the contact member 225 respectively contact the inner conductor section ends 208 and 209 at the points 258 and 259, and the contact mem-

ber 230 does not contact the inner conductor 98. The distance along the contact member 225 between inner conductor section ends 208 and 209 is such as to properly phase match the generator 80 to the cooking cavity 75 when thawed foods are disposed therein. When the solenoid coil 250 is energized by means to be described hereinafter, the rod 220 which acts as the plunger of the solenoid is moved into the position shown in FIG. 6. In this position the spring 254 is compressed against the flange 243 of bearing bracket 241 by the retaining nut 255 and the stop member 253 bears against the outer surface of the insulating spacer 218 thereby preventing further inward axial movement of the rod 220. Also, in this position the flanges 234 and 235 of the contact member 230 respectively contact the inner conductor section ends 208 and 209 at the points 256 and 257, and the contact member 225 is out of engagement with the inner conductor 98. The distance along the contact member 230 between the inner conductor section ends 208 and 209 is such as to properly phase match the generator 80 to the cooking cavity 75 when frozen foods are disposed therein.

Referring now to FIG. 2 of the drawing, there is shown a schematic and diagrammatical illustration of the control mechanism for the phase-matching apparatus 100. The microwave generator 80 is shown connected to a source of electrical power of the three-wire Edison type including a neutral line N that is electrically connected to ground potential, and a pair of outside lines L1 and L2 that are electrically insulated from each other and from the neutral line N, each of the three lines being connected to an insulating terminal block 301. The lines L1 and L2 are connected to the surface heating units 95 by a pair of conductors 302 and 303. The microwave generator 80 has a pair of input terminals 304 and 305 respectively connected to the lines L1 and L2, and a pair of output terminals 306 and 307 which are connected to the transmission line 85 through a capacitive coupling 308. In particular, the output terminal 306 is connected to the outer conductor 86 of the transmission line 85 as at 309 and the output terminal 307 is connected to the inner conductor 88 of the transmission line 85. The inner conductor 88 is connected through the phase-matching apparatus 100 to the antenna 89 and the outer conductor 86 is connected to the wall of the cooking cavity 75 as at 76. The wall of the cooking cavity 75 is grounded as at N. The phase-matching apparatus 100 is moved between its first and second positions by solenoid 310 which is electrically connected to the line L2 by the conductors 311 and 312. The solenoid 310 is mechanically coupled to the phase-matching apparatus 100 by plunger rod 315 which corresponds to the rods 120 and 220 in FIGS. 3 through 6. The solenoid 310 is energized through a selector switch generally designated by the numeral 320. The selector switch 320 includes an outer knob or dial 321 connected by a rotatable shaft 322 to insulator 323, the insulator 323 mechanically contacting a movable contact 325. Upon operation of the knob 321 to the position marked C, the insulator 323 is rotated by means of shaft 322 against the contact 25 thereby moving the contact 325 into connection with the fixed contact 326 thereby completing an electrical circuit from the line L2 to line N along the conductor 311, switch contacts 325 and 326, conductor 312 and the solenoid 310, and thereby energizing the solenoid. Upon being so energized the plunger 315 is moved from a first position shown to a second position thereby moving one contact member of the phase-matching apparatus 100 out of engagement with the inner conductor 88 and moving the other contact member into contact therewith. The dial 321 carries legends thereon C and T indicating respectively the cook and thaw positions. In the thaw position, as illustrated in FIG. 2 the switch 320 is open and the solenoid 310 is unenergized and the contact member 130 is in contact with the inner conductor 88 and transmission line 85. In this position

the generator 80 is essentially phase matched to the cooking cavity 75 when frozen foods are disposed therein, thus enabling heating of such foods in order to thaw them. Once thawed, the moisture in the food is in the liquid state thereby creating a mismatch between the generator 80 and the cooking cavity 75. The dial 321 may now be moved to the cook position for heating the thawed food. In this position the switch 320 is closed and the solenoid 310 is energized thereby moving the plunger 315 into its second position shown in FIG. 4 wherein the contact member 130 is out of engagement with the inner conductor 88 and the contact member 125 is connected therewith across the gap 110. In this position the generator 80 is properly phase matched to the cooking cavity 75 when thawed foods are disposed therein.

While FIG. 2 has illustrated the operation of the first embodiment of the phase-matching apparatus 100 as shown in FIGS. 3 and 4 of the drawing, the embodiment of FIGS. 5 and 6 may be operated in a completely analogous manner, the only difference being that the cook and thaw positions on the dial 321 would be reversed.

Referring now to FIG. 7 of the drawing, there is shown a performance chart for the microwave generator 80 used with 50 ohm transmission line in the electronic oven of this invention, the chart comprising a Rieke diagram superimposed upon a Smith chart. The data shown was obtained utilizing a series magnetic field in the generator 80 with an applied B+ potential of approximately 580 volts. As illustrated, a family of power curves 60 was obtained, the members of the family of curves 60 for 300 watts, 400 watts, 500 watts, 600 watts, 700 watts and 750 watts having been illustrated. A family of curves 61 showing the frequency of operation, has also been plotted. Superimposed upon these curves are a plurality of load lines 63 to 66, respectively indicating the loading characteristics of pork, beef, frozen foods and vegetables when these foods are disposed within the cooking cavity 75. As can be seen from FIG. 7, the loading characteristics of thawed meat loads disposed in the cooking cavity 75 are roughly centered about a radial line 67 in the phase octant between $\frac{1}{4}$ lambda and $\frac{5}{16}$ lambda. It can also be seen that the radial line 67, if extended through the center of the Smith chart will pass through the load lines 65 for frozen foods, thus indicating a phase mismatch of almost 180 degrees between a frozen load and a normal thawed meat load in the cooking cavity 75. Accordingly, when the transmission line 85 is of such a length as essentially to phase match the generator 80 with the cooking cavity 75 when thawed meat loads are disposed therein, there will be a rather severe phase mismatch if frozen foods are disposed in the cooking cavity 75 resulting in inefficient heating of the frozen foods. In particular, it can be seen from FIG. 7, that when the length of transmission line 85 is set properly to match thawed loads to the generator 80, between 700 watts and 750 watts of power will be delivered to the thawed meat loads while only a little more than 300 watts would be delivered to a frozen food load. Thus, by using the two-position phase-matching apparatus 100 or 200 of this invention, this serious problem of phase mismatching is substantially alleviated. More particularly, by use of the phase-matching device of the invention the frozen food load line 65 can be effectively transformed as at 63 to the phase octant occupied by the thawed meat load lines 63 and 64.

From the foregoing it will be seen that there has been provided an improved electronic oven including a microwave generator and a cooking cavity and a transmission line for coupling the microwave energy from the generator to the cooking cavity, and are as compatible of efficient heating both thawed and frozen foods. More particularly, there has been provided an improved two-position phase-matching apparatus for changing the effective electrical length of the transmission line for phase matching the generator to the cooking

cavity when thawed foods are disposed therein when the phase-matching apparatus is in one position and for phase matching the generator to frozen food load in the cooking cavity when the phase-matching apparatus is in its other position.

While there have been described what are at present considered to be the preferred embodiments of this invention, it will be understood that various modifications may be made therein, and it is intended to cover in the appended claims all such modifications as fall within the true spirit and scope of the invention.

What is claimed is:

1. In an electronic oven, structure defining a cooking cavity for heating both thawed foods wherein the water content thereof is in the liquid state and frozen foods wherein the water content thereof is in the solid state, a generator for generating high frequency electromagnetic wave energy, a transmission line coupling said generator to said cooking cavity and including a hollow outer conductor and an inner conductor, said inner conductor having a gap therein between said generator and said cooking cavity, said gap having a predetermined length, two-position bridging means including two electrically conductive members of different lengths not less than said predetermined length, said bridging means in the first position thereof bridging said gap with one of said conductive members for essentially phase matching said generator and said cooking cavity when thawed foods are disposed in said cooking cavity, said bridging means in the second position thereof bridging said gap with the other of said conductive members for essentially phase matching said generator and said cooking cavity when frozen foods are disposed in said cooking cavity, whereby to provide proper phase matching between said generator and said cooking cavity both when thawed foods are disposed in said cooking cavity and when frozen foods are disposed in said cooking cavity.

2. The oven as set forth in claim 1 and further including a selector mechanism for actuating said bridging means between the first and second positions thereof, said selector mechanism comprising a solenoid mechanically coupled to the said bridging means and a two-position selector switch and a source of electrical current electrically coupled to said solenoid through said selector switch.

3. The oven as set forth in claim 1, wherein said inner conductor is solid.

4. The oven as set forth in claim 1, wherein the difference between the lengths of said electrically conductive members is not greater than one half of the wave length of the operating frequency of said generator.

5. In an electronic oven, structure defining a cooking cavity for heating both thawed foods wherein the water content thereof is in the liquid state and frozen foods wherein the water content thereof is in the solid state, a generator for generating high frequency electromagnetic wave energy, a transmission line coupling said generator to said cooking cavity and including a hollow outer conductor and an inner conductor, said inner conductor including two spaced-apart sections terminating in a pair of spaced-apart ends providing a gap between said generator and said cooking cavity of a predetermined length, a support member extending into said gap and being movable between a first position and a second position, two electrically conductive contact members of different lengths not less than said predetermined length mounted on said support member, and drive means for moving said support member between said first position and said second position, one of said contact members being connected to said inner conductor section ends when said support member is in said first position for essentially phase matching said generator and said cooking cavity when thawed foods are disposed in said cooking cavity, the other of said contact members being connected to said inner conductor section ends when said support member is in said second position for essentially

phase matching said generator and said cooking cavity when frozen foods are disposed in said cooking cavity, whereby movement of said support member by said drive means between said first position and said second position serves to accomplish a proper phase matching between said generator and said cooking cavity both when thawed foods are disposed therein and when frozen foods are disposed therein.

6. The oven as set forth in claim 5, wherein one of said contact members is mounted on said support member adjacent to one end thereof and the other of said contact members is connected to said support member intermediate the ends thereof and said drive means is connected to said support member adjacent to the other end thereof.

7. The oven as set forth in claim 5, and further including an outer conductor section attached to said outer conductor and extending outwardly therefrom and accommodating said support member therein.

8. The oven as set forth in claim 5, wherein said drive means includes a source of electric current and a solenoid electrically coupled to said source and mechanically coupled to said support member.

9. In an electronic oven, structure defining a cooking cavity for heating both thawed foods wherein the water content thereof is in the liquid state and frozen foods wherein the water content thereof is in the solid state, a generator for generating high frequency electromagnetic wave energy and having a pair of output terminals, a transmission line coupling said generator to said cooking cavity and including a hollow outer conductor coupled to one terminal of said generator and an inner conductor coupled to the other terminal of said generator, said inner conductor including two spaced-apart sections terminating in a pair of spaced-apart ends providing a gap between said generator and said cooking cavity of a predetermined length, an elongated rod extending through said gap normal to the longitudinal axis of said transmission line adjacent to said gap and being movable between a first position and a second position, a first electrically conductive contact member having a first length slightly greater than said gap length and mounted on said rod intermediate the ends thereof, said first contact member bridging said gap when said rod is in said first position for essentially phase matching said generator and said cooking cavity when thawed foods are disposed in said cooking cavity, a second electrically conductive contact member having a second length exceeding said gap length by a length no greater than one-half of the wave length of the operating frequency of said generator and mounted on said rod adjacent to one end thereof, said second contact member bridging said gap when said rod is in said second position for essentially phase matching said generator and said cooking cavity when thawed foods are disposed in said cooking cavity, and drive means connected to said rod adjacent to the other end thereof for moving said rod between said first and said second positions, whereby movement of said rod by said drive means between said first position and said second position serves to change the effective electrical length of said transmission line to accomplish a proper phase matching between said generator and said cooking cavity both when thawed foods are disposed therein and when frozen foods are disposed therein.

10. The oven as set forth in claim 9, wherein said second contact member is substantially U-shaped and has a bight connected to said support member and a pair of legs extending toward said gap substantially normal to the axes of said inner conductor sections, the free ends of said legs respectively contacting said inner conductor section ends when said rod is in said second position.

11. The oven as set forth in claim 9, wherein said rod is axially movable.

12. The oven as set forth in claim 9, wherein both

said outer conductor and said inner conductor have a rectangular cross section.

13. The oven as set forth in claim 9, wherein said outer conductor has a pair of openings therein coaxial with each other and with said gap accommodating said rod therethrough, and further including two housings connected to said outer conductor and extending outwardly therefrom and respectively overlying said openings therein and respectively surrounding said second contact member and said drive means.

14. The oven as set forth in claim 9, wherein the length of said second contact member exceeds said gap length by a length in the range from about one-tenth of the wavelength of the operating frequency of said generator to about four-tenths of that wavelength.

15. In an electronic oven, structure defining a cooking cavity for heating both thawed foods wherein the water content thereof is in the liquid state and frozen foods wherein the water content thereof is in the solid state, a generator for generating high frequency electromagnetic wave energy and having a pair of output terminals, a transmission line coupling said generator to said cooking cavity and including a hollow outer conductor coupled to one terminal of said generator and an inner conductor coupled to the other terminal of said generator, said inner conductor including two spaced-apart sections terminating in a pair of spaced-apart ends providing a gap between said generator and said cooking cavity of a predetermined length, an elongated rod extending through said gap normal to the longitudinal axis of said transmission line adjacent to said gap and being movable between a first position and a second position, a first electrically conductive contact member having a first length not less than said gap length and mounted on said rod adjacent to one end thereof, said first contact member bridging said gap when said rod is in said first position for essentially phase matching said generator and said cooking cavity when thawed foods are disposed in said cooking cavity, a second electrically conductive contact member having a second length exceeding said gap length by a length no greater than one-half of the wavelength of the operating frequency of said generator and mounted on said rod intermediate the ends thereof, said second contact member bridging said gap when said rod is in said second position for essentially phase matching said generator and said cooking cavity when frozen foods are disposed in said cooking cavity, and drive means connected to said rod adjacent to the other end thereof for moving said rod between said first and said second positions, whereby movement of said rod by said drive means between said first position and said second position serves to change the effective electrical length of said transmission line to accomplish a proper phase matching between said generator and said cooking cavity both when thawed foods are disposed therein and when frozen foods are disposed therein.

16. The oven as set forth in claim 15, wherein both said outer conductor and said inner conductor have a circular cross section.

17. The oven as set forth in claim 15, wherein said outer conductor has an opening therein accommodating said rod therethrough and further including an outer conductor section attached to said outer conductor and extending outwardly therefrom and surrounding said second contact member.

18. The oven as set forth in claim 17, and further including a housing connected to said outer conductor section at the outer end thereof and extending outwardly therefrom and surrounding said drive means.

19. The oven as set forth in claim 15, wherein said second contact member is substantially U-shaped and has a bight connected to said rod and a pair of legs extending toward said gap substantially normal to the axes of said inner conductor sections, the free ends of said legs respec-

tively contacting said inner conductor section ends when said rod is in said second position.

20. The oven as set forth in claim 15, wherein the length of said second contact member exceeds said gap length by a length in the range from about one-tenth of the wavelength of the operating frequency of said generator to about four-tenths of that wavelength.

21. The combination for use in an electronic oven and the like comprising, a transmission line for transmitting high frequency electromagnetic wave energy of a predetermined frequency and including a hollow outer conductor and an inner conductor, said inner conductor having an insulating gap therein of a predetermined length, and two-position bridging means including two electrically conductive contact members of different lengths not less than said predetermined length, said bridging means in the first position thereof bridging said gap with one of said conductive members and said bridging means in the second position thereof bridging said gap with the other of said conductive members, whereby changing the position of said bridging means serves to change the effective electrical length of said transmission line to accomplish a shifting of the phase of the high frequency electromagnetic wave energy transmitted therealong.

22. The combination for use in an electronic oven and the like comprising, a transmission line for transmitting high frequency electromagnetic wave energy of a predetermined frequency and including a hollow outer conductor and an inner conductor, said inner conductor having a gap therein of a predetermined length, an elongated rod extending through said gap normal to the longitudinal axis of said transmission line adjacent to said gap and being movable between a first position and a second position, a first electrically conductive contact member having a first length slightly greater than said gap length and mounted on said rod intermediate the ends thereof for bridging said gap when said rod is in said first position, a second electrically conductive contact member having a second length exceeding said gap length by a length no greater than one-half of the wavelength of said predetermined frequency and mounted on said rod adjacent to one end thereof for bridging said gap when said rod is in said second position, and drive means connected to said rod adjacent to the

other end thereof for moving said rod between said first and said second positions, whereby movement of said rod by said drive means between said first position and said second position serves to change the effective electrical length of said transmission line to accomplish a shifting of the phase of the high frequency electromagnetic energy transmitted therealong.

23. The combination for use in an electronic oven and the like comprising, a transmission line for transmitting high frequency electromagnetic wave energy of a predetermined frequency and including a hollow outer conductor and an inner conductor, said inner conductor having a gap therein of a first predetermined length, an elongated rod extending through said gap normal to the longitudinal axis of said transmission line adjacent to said gap and being movable between a first position and a second position, a first electrically conductive contact member having a first length not less than said gap length and mounted on said rod adjacent to one end thereof for bridging said gap when said rod is in said first position, a second electrically conductive contact member having a second length exceeding said gap length by a length not greater than one-half of the wavelength of said predetermined frequency and mounted on said rod intermediate the end thereof for bridging said gap when said rod is in said second position, and drive means connected to said rod adjacent to the other end thereof for moving said rod between said first and said second positions, whereby movement of said rod by said drive means between said first position and said second position serves to change the effective electrical length of said transmission line to accomplish a shifting of the phase of the high frequency electromagnetic energy transmitted therealong.
